TEST CLIP

Robert B. Yongue, 4581 Palmer Ave.,
Jacksonville 10, Fla.
Filed Oct. 3, 1960, Ser. No. 59,913
6 Claims. (Cl. 200—158)

This invention relates to test clips and more particularly concerns test clips to replace crossarm-mounted insulators at preselected points along overhead lines, such as, telephone or telegraph lines.

A general object of this invention is to provide an improved test clip, and particularly, a test clip of the type which is attachable to a crossarm of a telephone pole and which is exposed to outside atmospheric conditions.

Another general object of this invention is to provide improved means for opening a telephone line for testing purposes and for closing the line after the test is made.

A specific object of this invention is to provide improved means for attaching a test clip to a crossarm of a telephone pole.

Another specific object is to improve the weather resistance of a test clip.

A particular object of this invention is to minimize spurious noise in a test clip.

The novel features which are believed to be characteristic of this invention are set forth with particularity in the appended claims. The invention itself, however, both as to its organization and method of operation, together with further objects and advantages thereof, may best be understood by reference to the following description taken in connection with the accompanying drawing, in which:

FIG. 1 is a perspective view of the test clip in accord with this invention which is shown mounted on a crossarm of a telephone pole;

FIG. 2 is an exploded, full transverse sectional view taken along line 2—2 of FIG. 1;

FIG. 3 is an exploded view of a portion of the test clip showing the inner spade ends of the extending wires; and

FIG. 4 is an exploded side elevational view, partially broken away, of the test clip in accord with this invention.

Referring now more particularly to the drawing of FIG. 1 the test clip 9, having copper wire lengths 11 and 12 projecting outwardly therefrom, is mounted on a wooden crossarm 13. Copper wire 12 is shown as being spliced to a telephone line 7 by a compression sleeve 8 and copper wire 11 is intended to be similarly spliced to the portion of line 7 extending in the opposite direction whereby the clip is interposed in series in the line 7. The test clip 9 includes a hollow body member 10 which comprises an upper body or shell portion 15, having a rain drip edge 16, and a lower body or shell 17 held together by body bolts 18 and nuts, including nut 63 shown in FIG. 4.

The test clip 9, in accord with the present invention, is more clearly shown in FIGS. 2, 3 and 4 wherein insulating inserts 19 and 20 are provided between body portions 15 and 17 diametrically opposite each other. Wires 11 and 12 pass respectively through inserts 19 and 20 and extend within the cavity 14 of the test clip body 10. Inserts 19 and 20 include respective integral flanges 21 and 22 which inwardly engage the body portions 15 and 17, thereby preventing inserts 19 and 20 from being pulled outwardly from cavity 14. Wires 11 and 12 are brazed to respective retainer plates 23 and 24, and the plates 23 and 24 respectively engage flanges 21 and 22 of inserts 19 and 20 to prevent the wires 11 and 12 from being pulled outwardly from cavity 14. The wires 11

2

and 12, inwardly of the retainers 23 and 24, are enlarged into respective spade ends 25 and 26. Spade 25 has a central opening 27 through which a shank 28 of a brass bolt 29 extends and the head 30 of the bolt 29 is brazed to spade 26. An insulating button in the form of an upset washer 31 fits around the shank 28 of the bolt 29, the button 31 having an annular upstanding central collar portion 32 which extends into and is engaged in opening 27 of spade 25. A vertical conductive shaft 33, having a skirt portion 34 preferably of copper or brass, screws down on the shank 28 of bolt 29. In its normal position skirt portion 34 seats against and makes contact with spade 25, as shown by the broken lines in FIG. 2. An electrical circuit is completed when the shaft is so screwed down from the lower spade 26, through bolt 29, to the shaft 33 and through its skirt 34 to the upper spade 25. The circuit is broken by merely unscrewing shaft 33 or bolt 29 sufficiently to separate skirt 34 from spade 25, as shown in full lines in FIG. 2.

The shaft 33 is slidably fitted through an insulating disk 40 which is mounted in an opening 41 in upper body member 15. Knob 35 is fittedly engaged on a ribbed upper end portion 38 of shaft 33 and held thereon by a bolt 36 engaged against a lock washer 37, the bolt 36 being threaded within shaft 33. The knob 35 provides the means to rotate shaft 33 and thereby to break the electrical connection between the skirt 34 and the upper spade 25 when the knob 35 unscrews the shaft 33 from bolt 29. The knob 35 also provides a rain shield for the insulating disk 40. The disk 40 is retained within the upper body member 15 by a retainer ring 42 and bolts 43.

A square crossarm bolt 50 projects through lower body member 17. A recessed portion 51 inwardly of body member 17 receives a weatherproof washer 52 seated therein against which an outwardly extending square head flange 53 of the bolt seats, forming a weatherproof seal. The bolt head 53 is retained within recessed portion 51 of body member 17 by retaining ring 54 held in place by bolts 55 screwed into the body member.

As can be best seen in FIG. 4, a gasket 59, comprising flat portions 60 and 61 and inserts 19 and 20, is provided between the body members 15 and 17 and a weatherproof seal is formed between body members 15 and 17 when body bolts 18 and nuts, including nut 63, assemble the test clip 9. In its preferred form as shown, a gasket 59 is of unitary construction.

The test clip 9 is provided with a pair of crossarm engaging spikes 65 and 66 which project inwardly into crossarm 13 to hold the test clip body 10 in fixed non-rotatable position when it is rigidly mounted on crossarm 13 by bolt 50 and nut 64. Since rotation of clip body 10 is prevented, wires 11 and 12 remain in opposite radial alignment exerting no substantial lateral force against the inserts 19 and 20 regardless of the tension of the line 7, whereby the chance of damage of the inserts is minimized.

The body 10 of test clip 9 is preferably formed of metal, as shown, which may be either a good or poor electrical conductor. It is contemplated however, that other suitable materials, such as glass or plastics, may be employed in forming the test clip body.

The test clips of the present invention are intended to be used at preselected points along the telephone lines and to replace the normal insulators at those points. The telephone lines are tested for faults by linemen whenever a fault occurs and the present invention enables a lineman to readily test the lines for faults. In testing for faults, a lineman turns the top knob of the respective test clip to open the line or lines to be tested. A telephone, for example, may then be connected to either of the now disconnected sections of the open line or lines. When the test is completed, the telephone or

other instrument is disconnected from the line or lines and the knobs of the one or more test clips are screwed down to again complete each line.

In making the test, it is important that insulating button 31 be dry so that it does not generate spurious noise. It is also important that the shaft insulator 49 and insulating inserts 19 and 20 be kept dry to reduce any noise which they might otherwise generate. The present test clip 9, having an enclosed hollow portion 14, effectively shields insulating button 31 from the weather elements. Likewise, knob 35 shields insulator 40 and rain drip edge 16 of upper body portion 15 partially shields insulating inserts 19 and 20. The introduction of noise by test clips for the purposes of the present invention is desirably minimized not only in order that the telephone lines may properly transmit the electrical information when in normal use with the test clips closed to complete the lines, but also to provide the best possible conditions under which the test may be made when the lines are opened by the test clips.

While only a certain preferred embodiment of this invention has been shown and described by way of illustration, many modifications will occur to those skilled in the art and it is, therefore, desired that it be understood that it is intended in the appended claims to cover all such modifications as fall within the true spirit and scope of this invention.

What is claimed as new and what it is desired to secure by Letters Patent of the United States is:

1. A test clip comprising a hollow body member having an upper shell portion and a lower shell portion, a pair of oppositely facing insulating inserts extending through said body member and being disposed between said shell portions, a respective wire extending inwardly of said body member through each said respective insert, each said wire having a spade end portion inwardly of said body member, a conductive bolt mounted through one of said spade end portions, an insulating button surrounding said bolt and disposed against said one end portion, the other spade end portion being seated on said button and being insulated thereby from said one end portion and said bolt, a shaft slidably mounted through an insulating disk disposed in said upper body portion, said shaft being threaded on said bolt, said shaft having a conductive skirt which selectively engages said other end portion thereby forming an electrical circuit path between said spade end portions, and means connected to

said shaft outwardly of said body member to selectively move said skirt into contact with said other end portion.

2. The test clip as defined in claim 1 wherein said means includes a knob secured to said shaft for turning said shaft and for shielding said disk.

3. The test clip as defined in claim 1 wherein said upper shell portion includes a rain drip edge for shielding said oppositely facing inserts.

4. The test clip as defined in claim 1 wherein each 10 said wire is connected to a respective retainer plate, each said retainer plate engaging respective said inserts thereby preventing said wires from being pulled outwardly from said body member.

5. A test clip for mounting on a crossarm of a 15 telephone pole comprising a body member having an upper shell portion and a lower shell portion, said lower shell portion including means for attachment to said crossarm, a pair of oppositely facing insulating inserts extending through said body member and being disposed between 20 said shell portions, said upper shell portion including a rain edge for shielding said inserts, a respective wire extending inwardly of said body member through each said respective insert, each said wire having a spade end 25 inwardly of said body member, a conductive bolt mounted through one of said spade ends, an insulating button surrounding said bolt and disposed against said one spade end, the other spade end being seated on said button and being insulated thereby from said one spade end portion and said bolt, a conductive shaft threaded on said 30 bolt, said shaft having a skirt for engagement with said other spade end, an insulating disk extending through said upper shell portion, said shaft being slidably mounted through said disk and extending outwardly from said upper shell, and a knob mounted on said shaft outwardly from said upper shell, said knob providing a rain 35 shield for said insulating disk, said knob being rotatable which selectively moves said shaft upwardly and downwardly, thereby respectively opening and closing an electrical circuit path between said spade ends.

6. The test clip as defined in claim 5 further comprising a pair of crossarm engaging spikes extending downwardly from said lower shell portion.
